UNITED STATES PATENT OFFICE.

WILLIAM F. SHUTT, OF BRICEVILLE, TENNESSEE.

INTERNAL-COMBUSTION ENGINE.

1,129,023.

Specification of Letters Patent. Patented Feb. 16, 1915.

Application filed November 3, 1913. Serial No. 798,978.

To all whom it may concern:

Be it known that I, WILLIAM F. SHUTT, a citizen of the United States, residing at Briceville, in the county of Anderson and State of Tennessee, have invented new and useful Improvements in Internal-Combustion Engines, of which the following is a specification.

This invention relates to improvements in explosive or internal combustion engines, and the primary objects of the invention are to provide an improved engine of this type whereby wear of the cylinders and pistons is reduced to a minimum, correct and tight fitting of the valves is maintained, and all the bearings are accessible and adjustable, the pistons according to the present invention being connected to a cross-head which operates in a straight line and sustains the weight of the pistons, and the valves being provided with means for rotating them automatically to distribute the wear evenly thereon.

To these and other ends, the invention consists in certain improvements, and combinations and arrangements of parts, all as will be hereinafter more fully described, the novel features being pointed out particularly in the claims at the end of the specification.

In the accompanying drawings:—Figure 1 is a top plan view of an internal combustion engine constructed in accordance with the present invention; Fig. 2 represents a longitudinal section through the engine as shown in Fig. 1 and in the plane of two of the cylinders; Fig. 3 is an end elevation of the invention, partly in section, and viewed from the left in Figs. 1 and 2; Fig. 4 represents a transverse section on the line 4—4 of Fig. 1; Fig. 5 represents a section on the line 5—5 of Fig. 1 showing the arrangement of the valves; Fig. 6 is a top plan view of the valve actuating members and the co-operative cam shaft; Fig. 7 is a detail view showing a part of the valve-rotating mechanism; Fig. 8 is a perspective view of one of the shims which is interposed between the pistons and cross-head; Fig. 9 is a detail view showing the lower end of one of the valve stems and the gear thereon for rotating the same; Fig. 10 is a perspective view of one end of the cross-head showing the bearing slide.

Similar parts are designated by the same reference characters in the several views.

Internal combustion engines constructed in accordance with the present invention are adapted to be used for various purposes. The preferred embodiment of the invention is shown in the accompanying drawings and will be hereinafter described in detail, but it is to be understood that this form of the invention is shown as an example thereof and that modifications and changes may be made and equivalent constructions employed which will come within the scope of the claims at the end of the specification.

In the construction shown, 1 designates a suitable base or frame to support the parts of the invention in correct relation. In the present instance, the engine is of the four cylinder type operating on the well known four-cycle principle, it embodying two pairs of cylinders 2 and 3 arranged in opposed relation, that is to say, the cylinders of one pair are in axial alignment with those of the other pair. Each pair of cylinders is preferably cast integral and may be conveniently secured to opposite sides of the base or frame 1 by means of lugs 4 and 5 forming parts of the castings and secured to the frame or base by bolts. Each cylinder casting is formed with valve pockets or chambers 6, and each cylinder is provided with a pair of valves 7 and 8 to control the admission of fuel to the cylinder and the exhaust of the burned fuel or gas therefrom. These valves are timed to operate in the same manner as those of the ordinary four-cycle engine and hence it is unnecessary to explain the same in detail. A piston 9 is fitted to reciprocate in each cylinder, the pistons in the axially aligned cylinders being connected to reciprocate in unison by a member 10 which, according to the present invention forms a rigid connection between the pistons. These members 10 are of ample strength to sustain the force of the explosions exerted on the pistons. A cross-head 11 is operatively connected to the members 10 and serves to transmit the reciprocatory movements of the pistons when on their power strokes to the crank-shaft which will be hereinafter described, and to transmit motion from the crank-shaft to the pistons to operate them upon their compression strokes. This cross-head is mounted to reciprocate in guides 12 which are formed at opposite sides of the base or frame 1. Adjustable or removable bushings

or slides 13 are preferably fitted on the ends of the cross-head 11 and operate in the guides 12, the inner sides of these bushings or slides having flanges 14 to engage 5 the inner sides of the base or frame and thereby prevent end thrust of the cross-head. The ends of the cross-head are connected by the connecting rods 15 to the wrist or crank-pins 16 of the crank-shaft 17, fly 10 wheels 18 being fixed on the crank-shaft in the present instance and carrying the wrist or crank-pins 16. Power generated by the engine can be taken from the crank-shaft 17 by any suitable means. The bearings 19 15 for the crank-shaft 17 are exposed and therefore they are readily accessible for oiling, inspection or adjustment. The bearings which connect the ends of the rods 15 to the wrist pins 16 and the cross-head respectively are also exposed and adjustable.

According to the present invention, the weight of the pistons is not imposed on the cylinders, that is to say, the weight of the pistons is balanced and supported by the cross-head 11, thereby minimizing wear of the pistons and cylinders. This is accomplished in the construction shown by providing each member 10 with a spring 20, a coiled compression spring being shown in 25 the present instance which is inclosed in a housing 21 formed as a part of the member 10, and the upper end of this spring engages an abutment 22 which is preferably threaded or otherwise adjustably fitted 30 to the upper end of the housing 21, and the lower end of the spring bears on the top of the cross-head 11. Sufficient movement is provided between the cross-head 11 and each member 10 and the spring 20 and so 35 adjusted that it will balance the weight of the pistons which are connected to the member 10, and this weight will be sustained by the cross-head 11. In order to provide for any lack of alinement between the member 40 10 and the cross-head 11, a compensating or universal joint is provided between these parts. In the construction shown, a pair of bearing members 23 are secured to the opposite sides of the cross-head 11, these 45 bearing members having spherical or convex heads and spherical or concave seats 24, one of which rests against the member 10 and the other against a shim 25 in positions to receive the spherical heads on the cross-head. The tapered shim 25 is provided to 50 take up wear between these members forming the universal or compensating joint, the shim being movable transversely in the respective member 10 behind one of the 55 bearing seats 24 and may be held in different adjusted positions by the screws or bolts 26. A compensating or universal joint of this character relieves the pistons of any lateral strains that might otherwise be imposed upon them, due to lack of alinement

between the members 10 and the cross-head 11.

The present invention provides means for rotating the valves in order to distribute the wear evenly thereon. For this purpose the 70 lower end of the stem 27 in each valve is provided with the usual seat or collar 28 to support the valve closing spring 29, and a gear wheel 30 is fixed to the valve stem and serves as means for rotating it. The 75 gear 30 may be fixed to the valve stem in different ways, the valve stem in the present instance being formed with a square or angular groove 31, and a tapered sleeve in the form of square or angular sections 32 80 is fitted into the groove 31 in the valve stem and engages in a tapered angular hole in the gear 30, the downward pressure of the spring 29 on the gear 30 binding the latter to the valve stem. As the spring-supporting seat 28 is non-rotatable while the gear 30 rotates, a ball-bearing 33 is preferably interposed between these parts and the gear 30 may carry lugs 30^a engaging in a circumferential groove 28^a in the seat 28 to 90 prevent displacement of the balls of the bearing 33. The gear 30 is arranged to operate with a spiral gear 34 which is arranged beside it and is journaled in a bracket 35 fixed to the engine frame. Each spiral gear 34 is provided with a ratchet wheel 36 and a suitable number of pawls 37 are provided which coöperate with the ratchet wheel, permitting the gear 34 to rotate in one direction and preventing backward 95 rotation thereof. With such an arrangement, when each valve moves toward closed position, the spiral gear 34 is held from rotation by the ratchet wheel and pawl, and the vertical movement of the gear 30 thereon causes the latter and the valve stem to which it is fixed to rotate a partial turn. When the valve lifts toward open position, the gear 34 will rotate idly while the valve 100 stem remains in the position in which it was previously rotated, it being again rotated a partial revolution when again opened. In this way, wear upon the seat of the valve is distributed evenly and the slight grinding action of the valve on its seat will maintain a perfect fit between these parts. Obviously, the reverse action can be used, in which case the valve will rotate during lifting of the valve. The valves may 105 be operated in any suitable way, a cam shaft 38 being shown in the present instance which serves to actuate all the valves through the medium of levers 39 which are fulcrumed on pivots 40, the outer ends of these levers having adjustable valve lifters 41 thereon. The cam shaft can be actuated in different ways, it being provided in the present instance with a sprocket wheel 42 which coöperates with a chain 43, the latter being driven 110 by a sprocket wheel 44 which is connected 115 120 125 130

to rotate with a gear wheel 45, and this gear wheel coöperates with a gear wheel 46 fixed to the crank-shaft 17.

An explosive engine constructed in accordance with the present invention is more durable than such engines as heretofore constructed, as the pistons and cylinders are not subject to lateral thrust and wear, due to the angular motion of the connecting rod, the weight of the pistons is supported in a way which avoids wear of the lower sides of the pistons and cylinders, thereby prolonging the durability of these parts, the valve-rotating feature of the present invention insuring correct fitting of the valves, and as all the bearings of the moving parts of the engine are accessible, their condition can be determined by inspection and they may be easily lubricated and adjusted.

20 I claim as my invention:—

1. In an internal combustion engine, the combination of horizontal opposed cylinders, pistons connected rigidly and reciprocable in said cylinders, a reciprocatory cross-head and cooperating guides, a crank shaft operatively connected to said cross-head, and a universal joint connecting said cross-head and said pistons and embodying means for relative vertical adjustment between the cross-head and pistons.

2. In an internal combustion engine, the combination of horizontal opposed cylinders, pistons connected rigidly and reciprocable in said cylinders, a reciprocatory cross-head, a crank shaft having a pair of cranks thereon, a pair of pitmen connecting said cranks with the ends of said cross-head, a universal joint connecting said cross-head and said pistons, said cross-head supporting the weight of said pistons, and bearings slidably supporting the cross-head.

3. In an internal combustion engine, the combination of horizontal opposed cylinders, pistons connected rigidly and reciprocable in said cylinders, a reciprocatory cross-head, and supporting guides therefor, a crank shaft operatively connected to said cross-head, compensating bearings interposed between the cross-head and said pistons, and a vertically acting spring interposed between the cross-head and pistons and supporting the weight of the latter.

In testimony whereof I have hereunto set my hand in presence of two subscribing witnesses.

WILLIAM F. SHUTT.
